US00D509493S

(12) **United States Design Patent** (10) Patent No.: **US D509,493 S**
Winebrenner et al. (45) Date of Patent: **** Sep. 13, 2005**

(54) **WIRELESS MOBILE TELEPHONE**

(75) Inventors: **Jon Winebrenner**, Richmond (CA); **Mark Hoeveler**, Portland, OR (US); **David Sayler**, Portland, OR (US); **Ichiang Sun**, Portland, OR (US); **Jamian Russell Cobbett**, Portland, OR (US); **Stephen Matthew McCallion**, Portland, OR (US)

(73) Assignee: **Sierra Wireless, Inc.**, Richmond (CA)

(**) Term: **14 Years**

(21) Appl. No.: **29/187,775**

(22) Filed: **Aug. 6, 2003**

(51) LOC (8) Cl. **14-03**

(52) U.S. Cl. **D14/138**; D14/345

(58) Field of Search D14/137, 138, D14/218, 147-148, 247-248, 144, 341-347; 379/433.01-433.13, 419, 434, 428.01-428.04, 420.01-420.04, 440; D10/65, 78; 455/550.1-90.3; D21/517; D13/168; D18/2, 7; 345/168, 169

(57) **CLAIM**

The ornamental design for a wireless mobile telephone, as shown and described.

DESCRIPTION

FIG. 1 is a perspective view of the wireless mobile telephone.

FIG. 2 is a perspective view of the wireless mobile telephone with an open keyboard.

FIG. 3 is a front view of the wireless mobile telephone.

FIG. 4 is a front view of the wireless mobile telephone with an open keyboard.

FIG. 5 is a right side view of the wireless mobile telephone.

FIG. 6 is a right side view of the wireless mobile telephone with an open keyboard.

FIG. 7 is a left side view of the wireless mobile telephone.

FIG. 8 is a left side view of the wireless mobile telephone with an open keyboard.

FIG. 9 is a top view of the wireless mobile telephone.

FIG. 10 is a top view of the wireless mobile telephone with an open keyboard.

FIG. 11 is a bottom view of the wireless mobile telephone; and,

FIG. 12 is a bottom view of the wireless mobile telephone with an open keyboard.

The broken line showings throughout the views are for illustrative purposes only and form no part of the claimed invention.

1 Claim, 7 Drawing Sheets
